AUTOMATIC LIQUID-FUEL CONTROL.

1,060,221.

Specification of Letters Patent. Patented Apr. 29, 1913.

Application filed January 18, 1912. Serial No. 671,828.

To all whom it may concern:

Be it known that I, ELMER E. WICKERSHAM, a citizen of United States, residing at Newman, in the county of Stanislaus and State of California, have invented new and useful Improvements in Automatic Liquid-Fuel Controls, of which the following is a specification.

This invention relates to automatic liquid fuel control.

10 The object of the present invention is to provide a liquid fuel control in combination with a steam generating plant.

15 The burning of crude oil requires first, that it be thoroughly atomized; and second, thoroughly supplied and mixed with a given quantity of air to secure the best results and a maximum firing efficiency.

20 In many large steam power plants there are employed boilers of different horse-power in the one establishment.

25 It is one of the objects of the present invention to automatically control the volume of oil and steam for the vaporization of the same which is delivered to the furnaces of the several boilers irrespective of the differences in the horse-power of the boilers.

30 It is also an object of the invention to provide in an oil burning system a master controlling device connected to the main steam head and through said device control the flow of liquid fuel, vaporizing steam and air as they are admitted to the furnaces of the boiler for the combustion of the liquid fuel.

35 When boilers of different horse-power are used in steam plants, it is necessary that provision be made so that no one of the boilers will be over or underfed with liquid fuel.

40 It is one of the important features of the invention to so regulate the admission of liquid fuel and vaporizing steam that any boiler irrespective of its horse-power will always receive a given or definite quantity of fuel and vaporizing medium best adapted for each particular boiler.

45 The invention consists of the parts and the construction and combination of parts as hereinafter more fully described and claimed, having reference to the accompanying drawings, in which—

50 Figure 1 is a diagrammatic view representing the fuel controlling system as attached to a boiler plant. Fig. 2 is a sectional detail view of a burner equalizer.

Fig. 3 is a vertical sectional view of the secondary controller, D. Fig. 4 is a part sectional view and part elevation of the master controlling device, C.

60 In the illustrated embodiment of my invention I have shown at A a pressure chamber, of suitable proportions, which is appropriately connected to an oil pump Y to which oil may be conveyed from any suitable source and from which it is delivered through the discharge pipe R to a manifold or header T, shown as extending along the front of a series of boilers 1 and 2, which, for the purpose of this invention, shall be 70 considered as of different horse-power as designated one hundred and two hundred respectively.

75 Steam is admitted into the equalizing pressure chamber A from a suitable form of master controller C, being provided with a hand-wheel B so that the apparatus may be adjusted to admit a greater or lesser quantity of steam into the chamber A. Steam is conducted to the master controller 80 C, Fig. 4, through a pipe 3 which is connected to the main steam drum 4. Steam from the main drum or line 4 is conducted at full pressure into the master controller C through which it may pass at reduced pressure 85 into the equalizer A, thence to the pump and also from the equalizer A through a branch 5, a portion of which is conducted to a damper controller E which is actuated to open the dampers I of the boilers by 90 the pressure of steam from chamber A passing through master controller C.

95 At each variation of pressure in the steam chamber A there is a consequent movement of the piston-rod 6 of the damper controller E; this piston-rod 6 being connected to and actuating a rocker-shaft K which has suitable connections, as links H, with the several dampers I of the furnaces.

100 Branching from the steam pipe 3 which feeds steam to the master controller C, there is a pipe 7 by which steam under full pressure from the main 4 is admitted to a secondary controller D of suitable character, the function of which is to reduce the pressure of steam coming from the pipe 7 so that the steam may be discharged from the controller D through a pipe P to a steam manifold S extending along the front of the boilers substantially parallel with and are 110 shown as above the oil manifold T. The operation of the secondary controlling device

D is dependent upon variations of pressures in the steam chamber A; the controller D being connected to the branch 5 as shown so that steam from the chamber A operates upon the mechanism of the secondary controller D which determines the pressure of the steam issuing from the controller to the pipe P and through this to the manifold S. In other words, after the master controller 10 C has been adjusted by means of the hand-wheel B steam is admitted from the main line 4 in which it may exist at one hundred pounds pressure and the controller will then cut down the pressure of steam so that it 15 will be admitted into the chamber A somewhat lower than in the main line 4.

The steam from the chamber A is operative upon the pump and the volume of oil traveling through the pipe R to the oil 20 manifold T in front of the furnaces is naturally determined by the pressure of steam from the chamber A. For each and every variation of pressure in the chamber A there is a constant variation in the volume of 25 fluid discharged by the pump Y.

If there is a demand on the steam plant for a considerable quantity of steam, there may be a momentary reduction of the pressure in the main line 4, and this reduction 30 of the pressure is compensated for by the master controller C which automatically operates to admit a larger volume of steam to pass into the equalizing chamber A thus driving the pump faster to increase the supply of oil and consequently increase the fire 35 under the boilers. Simultaneously with the increase of pressure in the chamber A there will be an increase of pressure in the secondary controller D which will automatically 40 operate to admit a larger volume of steam to flow into the pipe P and to the steam manifold S, and coincident with the increase of pressure in the pipe 5 from the chamber A the damper controller E will 45 operate and through its connections open the dampers I for the flow of a larger volume of air.

The master controller, C, may be of any appropriate character, and in Fig. 3, I illustrate a construction suitable for the present 50 purposes. This construction embodies a suitable casing upon which is mounted a diaphragm, 30, upon the top of which presses a balancing spring 31, and by placing the 55 steam pressure, balancing spring, on the top of the diaphragm, with the steam pressure beneath the diaphragm, which carries the throttle valve, 32, and stem, 33, I am enabled to do away with stuffing boxes of movable 60 parts and thereby eliminate all excessive friction. The spring 33, is made adjustable by any well known means, and a threaded valve seat, 35, is mounted within the casing and is adjustable by means of the hand wheel, 65 B, having a stem, B', engaging the valve seat.

By raising or lowering the valve seat, 35, the effect would be as follows: The boiler pressure from the supply pipe, 3, connected to the inlet side of the master controller, C, would operate to hold the diaphragm, 30, 70 and valve, 32, in a higher or lower plane to vary the quantity of steam passing through the controller without making any adjustment of the spring balancing steam pressure. The spring, 31, is adjusted to balance 75 a certain percentage of the maximum boiler steam pressure with the valve seat, 35, at one half its maximum height. Any further adjustment of the valve seat in the master controller, C, determines the boiler steam 80 pressure, the quantities of oil fed to the furnace, the atomizing of the steam, and the quantity of oxygen passing to the furnace for combustion.

The secondary controller, D, may be of 85 any suitable type and one type suitable for the purpose I have shown in Fig. 4, as comprising two diaphragms, 40, 41, which may be either of equal or unequal diameters, said diaphragms being spaced apart by a traveling push rod, 42. The diaphragms are arranged to oppose each other and to vary the position of a cylindrical steam valve, 43, which has a stem, 44, which is connected to the push rod, 42, which in turn is connected 95 to the diaphragms. This stem serves as a push rod and it carries a collar, 44, which supports a lever, 45, one end of which is pivotally mounted and the other end is connected to and held down by a suitable spring tensioning device, 46. To vary the tension of the spring device, 46, in effect varies the 100 diameters of the diaphragms; in other words the steam pressures of the opposing sides of the diaphragms must be varied to effect a 105 balance of pressures on the opposite ends of the push rod, 42, to move and hold the steam valve, 43, open or closed.

Referring again to Fig. 1, and considering that the valves, 11 and 12, are wide open, 110 the flame has started in the furnace and that there is steam pressure on the boilers. The hand wheel, B, on the master controller, C, is adjusted to permit steam to pass through one pipe, 3, to the pressure chamber, A, and 115 accumulate pressure enough therein to operate the oil pump, Y, to force oil through the discharge pipe, R, to the manifold, T, and finally to the furnace. Pressure in the chamber, A, has now operated through the 120 branch, 5, and the damper controller, E, to open the dampers in the stack. Pressure from the branch 5, operates on top of the diaphragm, 40, of the secondary controller, D, and through the push rod, 42, the lower 125 diaphragm, 41, and the valve, 43, are operated in a downward direction to allow steam to pass through the pipes, 3 and 7, and the valve, 43, to exert an upward pressure on the bottom of the lower diaphragm, 41, and

accumulate a pressure in the pipes, P and S, greater or less than the downward pressures exerted by the top diaphragm, 40, and push rod, 42.

5 I will now consider that the boiler steam pressure has risen above its former pressure and exerts a greater upward pressure on the diaphragm, 30, in the master controller, C, thus closing the valve, 32, partly, and reducing the steam pressure in the pressure chamber, A, which will effect the damper controller E, to close the dampers, correspondingly, also to reduce the downward pressure on top of the diaphragm, 40, of the secondary controller, D, allowing an upward movement of both diaphragms and valves to partly close the valve and to reduce the upward pressure to a point equal to the downward pressure. The partial closing of the 10 valve in the master controller depletes the supply of steam to the pump, Y, and consequently reduces the flow of oil to the furnace at the same time the above pressures were being decreased.

15 25 From the foregoing it will be seen that for every reduction of pressure of steam in the main line 4 from any cause the master controller C will instantly respond automatically to admit a greater volume of steam to the chamber A, and from thence to the boiler and the secondary controller D for admitting more steam to the boilers, and to the damper controller E for permitting a greater volume of air to flow through the 20 furnace; this simultaneous operation being designed to most efficiently and rapidly build up or decrease the fire by admitting given proportions of air, steam and oil as the immediate necessity requires.

25 40 When there are several boilers of different horsepower located in a steam plant, it is necessary that the volume of steam, oil and air in each of the several boilers be in exact proportions to the capacity of the boilers and if some means were not provided for so controlling and proportioning the steam, oil and air for each boiler according to its requirements, the boilers would be either overfed or underfed with great destructive 45 consequences and loss of efficiency. To that end an important feature of the invention is the provision of means whereby each boiler, though different in horse power, will receive the most efficient quantity of oil, steam and air at all times; the pressures of the same 50 being automatically controlled by the apparatus hereinbefore described. I have found in actual practice that this determination of the steam and oil taken from the manifolds S and T can be minutely, accurately and 55 constantly regulated as each case necessitates by the introduction of a connection 10, shown in Fig. 2, of which there is one connected at each end of the burners V, into 60 which oil and steam are conducted respec-

tively through the connections 10; these being coupled to upper and lower valves 11 and 12 respectively which control the flow of steam from the pipe S into the burner V; the lower valve 12 controlling the flow of oil from the manifold T into the burner.

65 The interposition of the peculiar connections 10 between the valves 11 and 12 and the burner V insures that once the valves have been opened wide for the admission of fluid at full pressure from the manifolds S and T, the operator need no longer watch or adjust the valves, since the devices 10 effectively control and deliver to the burner V definite quantities of oil or steam. 80

75 The devices 10 are clearly shown as having contracted channels 13 at one end communicating with enlarged channels 14 which open into the burner V. Since each of the manifolds S and T are charged with steam 85 or oil respectively at given or varying pressures, and then if the valves 11 and 12 be thrown wide open oil or steam will have access to its respective connection 10 and may flow through the restricted orifice or channel 13 only in restricted or definite proportions.

80 90 95 In the case of the one hundred horse-power boiler a connection 10 is used which will deliver steam or oil in certain quantities to the burner B, and in the case of the two hundred horse-power boiler a connection 10 will be used in which the restricted orifice 13 will be, for instance, twice the transverse area of the equalizing orifice of the 100 smaller boiler. Thus each of the boilers whatever their respective horse-power may be will be fed with a predetermined quantity of oil or steam which must flow to the burners through the equalizing connections 10, 105 each being provided with a restricted channel, as 13.

100 110 Manifestly for every variation of pressure in the manifolds S or T there will be an increase in the volume of fluid traveling through the connections 10, but there will be no requirement for any adjustment of the valves 11 or 12 since these may be opened to their fullest extent, and the attention of the operator is no longer required inasmuch as 115 the equalizing devices 10 will constantly control the volume of oil or steam, as the case may be, flowing.

115 120 Having thus described my invention, what I claim and desire to secure by Letters Patent is—

1. In an oil burning system, the combination with steam boilers, of hydrocarbon burners under the boilers, a master controller for automatically operating to maintain a given pressure in the boilers and deriving steam therefrom, said controller having manually adjustable parts, and means governed by the controller for synchronously varying the quantity of oil, air and steam 125 130 135

utilized at the boilers for combustion, said means including a distributing, equalizing chamber into which steam is delivered by the controller, an oil pump operated by steam 5 from said chamber and connected to the burners by feed pipes, a damper mechanism for the boilers operative by steam from said distributing chamber, and a steam-feeding device connected to the burners and connected to said chamber for operation by variable pressures therein, said damper, pump and steam-feeding device automatically operating under variations of pressure of steam from the equalizing chamber in 10 which the pressure is varied inversely by the controller as to the variation of boiler pressure.

2. In an oil burning system, the combination with steam boilers, of hydrocarbon 20 burners under the boilers, a master controller for automatically operating to maintain a given pressure in the boilers and deriving steam therefrom, said controller having manually adjustable parts, and means 25 governed by the controller for synchronously varying the quantity of oil, air and steam utilized at the boilers for combustion, said means including a distributing, equalizing chamber into which steam is delivered by the controller, an oil pump operated by steam 30 from said chamber and connected to the burners by feed pipes, a damper mechanism for the boilers operative by steam from said distributing chamber, a steam-feeding device 35 connected to the burners and connected to said chamber for operation by variable pressures therein, said damper, pump and steam-feeding device automatically operating under variations of pressure of steam from the 40 equalizing chamber in which the pressure is varied inversely by the controller as to the variation of boiler pressure, and restrictive

elements peculiar to each boiler for admitting thereto from the oil feed pipes a quantity proportionate to the boiler size and to 45 admit variable quantities proportionate to variable pressure from the master controller.

3. In a liquid fuel control for steam plants, the combination with oil burners, of a steam conductor connected to the burners 50 and deriving steam from the boiler for conveying steam for atomizing oil at the burners, a regulator in said conductor having manually adjustable means whereby a desired ratio of steam to burners in proportion to oil is effected, said regulator having diaphragms, one of which is exposed to boiler pressure from the conductor, a master controller having manually adjustable means for operating to maintain a given boiler 60 pressure, and having a steam inlet from the plant boilers and an outlet for steam, said regulator having a piston exposed to pressure of steam from the outlet of the controller for varying the steam to burner synchronously with changes of pressure in the plant boilers, a pump for feeding oil to the burners and operated by steam from the controller, and a draft controlling mechanism for the plant operated by steam from the 70 controller, said controller being operated by increase of steam pressure in the plant to decrease steam to said pump, mechanism and regulator, and operating automatically to increase steam to said parts when boiler pressure decreases. 75

In testimony whereof I have hereunto set my hand in the presence of two subscribing witnesses.

ELMER E. WICKERSHAM.
